UNITED STATES PATENT OFFICE

JOHN LAFAYETTE BABER, JR., OF LYNCHBURG, VIRGINIA

ACCOUNTING SYSTEM AND APPARATUS

Application filed December 9, 1926. Serial No. 153,704.

This invention relates to accounting systems and apparatus for use in factories and other places of business where it is essential that complete and accurate records be made of the number and nature of tasks completed by each employee.

The salient purpose of the invention is to enable separate employer and employee records, pertinent to each completed task, to be made in a single operation thereby saving time besides insuring exact duplication of the records.

Another purpose of the invention is to further simplify the recording procedure by the provision of a unitary record receiving medium in combination with marking means operable to mark duplicate indicia on different portions of the receiving medium and to simultaneously detach one of the marked portions for delivery to the employee.

A still further purpose of the invention is to prevent incomplete and inaccurate marking of the receiving medium through the instrumentality of a safety device functioning to permit operation of the marking means only when said marking means is disposed in proper marking relation to the receiving medium.

Briefly stated the invention consists in providing a record sheet in combination with a marker operable to mark duplicate indicia on different portions of the sheet and to simultaneously detach one of the marked portions from the body of the sheet. The marking may be accomplished by a printing, cutting, punching, embossing or like operation while the detachment of one of the marked portions of the sheet may be effected in various ways through the instrumentality of suitable cutting edges operating in unison with the marking means. In order to insure proper positioning of the marker with respect to the record receiving medium prior to the actual marking operation the marker is equipped with a device normally holding the marker inoperative and adapted to be engaged and displaced by the record receiving medium only when the latter and the marker are relatively positioned to insure accurate placing of the record indicia.

In the present instance I have elected to disclose the invention with particular reference to its use in a shoe factory for recording, in duplicate, the completion of each operation in the manufacture of a shoe and the 55 time clock number or other symbol identifying the operator. In this application of the invention use is made of a record receiving medium which may consist of a sheet of any suitable material. The body portion of the 60 sheet, which is used as a shop sheet, serves as the employer or factory record while the marginal portion of the sheet is subdivided by ruled or scored lines to provide coupons detachable from the body of the sheet for 65 retention by the employee as his evidence of the completion of a task concerning which record indicia is marked on both the body of the sheet and the said coupon. Each sheet thus used may be provided with an identifying 70 serial number and the same serial number is preferably marked on each of the several coupons. In addition, each coupon is printed or otherwise marked to indicate a particular operation in the manufacture of a 75 shoe and duplicate marking may also be made on the body of the sheet opposite the attached end of the coupon. Duplicate notations regarding the labor cost incident to each operation may be also marked both on the body of 80 the sheet and on the coupons. It will be understood that the serial number and the markings relative to the nature of the various operations and the labor costs incident thereto are printed or otherwise provided on 85 the sheet and coupons in the original production of the sheet and are of a more or less permanent nature. The operation title and cost markings on the body of the sheet are so located with reference to the marginal coupons that by glancing at the marginal portion of the body of the sheet from which a coupon has been detached, as hereinafter described, the nature of the operation and the labor cost represented by the detached coupon 90 may be readily ascertained. In lieu of this arrangement the body of the sheet may have merely the cost of each operation printed thereon opposite the attached end of the coupon representing that particular op- 95 100

eration in which event the nature of the operations represented by the detached coupons may be ascertained by placing the shop sheet on a master sheet of similar construction so that the coupons on the master sheet serve as a substitute for the coupons detached from the shop sheet in checking up the various operations represented by the detached coupons.

10 For use in connection with the aforementioned shop sheet each employee is provided with an implement having duplicate markers for marking the time clock numbers or other symbol identifying the employee on one of the coupons and on the body of the sheet simultaneously to indicate both on the body of the sheet and on the coupon that the particular operation represented by the coupon has been completed by that particular employee. To prevent loss of time incident to manual detachment of the coupons the implement is preferably provided with cutting edges for severing the coupon from the sheet simultaneously with the marking operation. In addition to the aforesaid cutting and marking means the implement may also be provided with a numbering device actuated by each operation of the implement to consecutively number the marked coupons so that by comparing the first and the last numbered coupons turned in by any employee for a given period the number of operations completed by the employee for such period may be readily determined.

35 For a more complete understanding of the specific construction and application of the invention generally outlined in the foregoing reference will now be had to the following detailed description taken in connection with the accompanying drawings in which,

Figure 1 is a view in side elevation of the marking and cutting implement.

Figure 2 is a vertical longitudinal sectional view.

45 Figure 3 is a plan view of one of the detached lever members of the marking implement.

Figure 4 is a view similar to Figure 3 of the remaining lever member.

50 Figure 5 is a view similar to Figure 1 but partly broken away to show the pawl and ratchet mechanism of the coupon numbering device.

Figure 6 is a sectional view taken along the line 6—6 of Figure 1.

Figure 7 is a sectional view taken along the line 7—7 of Figure 1.

Figure 8 is a view partly in side elevation and partly in vertical section of a modified form of cutting and marking implement.

Figure 9 is a fragmentary detailed view showing the construction of one of the cutting edges.

65 Figure 10 is a fragmentary view of the shop sheet or record receiving medium.

Proceeding now to a more detailed discussion of the drawings reference will be had initially to the record receiving medium or shop sheet shown in Figure 10. As previously stated, the body portion 5 of the sheet serves as the employer's or factory record while the marginal portion of the sheet is scored or ruled as indicated at 6 to define a plurality of marginal coupons 7. The body of the sheet is marked, preferably at the top, with an identifying serial number (not shown) and this serial number is also marked on each of the coupons as indicated at 8. Title legends 9, representing different operations in the manufacture of a shoe are marked in duplicate on the coupons and on the marginal portion of the body 5 of the sheet immediately adjacent the attached ends of the coupons and it is also preferred that each coupon and the marginal portion of the body of the sheet at the attached end of the coupon, be marked in duplicate, as indicated at 10 to designate the labor cost of the operation represented by the coupon.

70 The marking implement provided for use in connection with the aforementioned sheet consists of a lower member 12 equipped with side flanges 13 carrying, at their forward ends, a pivot 14 upon which is mounted the forward ends of an upper member 15, the rear ends of both members being normally spaced apart by a spring 16 and shaped to provide handle members 17. Immediately in the rear of the pivot 14 members 12 and 15 are provided with opposing blocks 18 and 19 pinned thereto as indicated at 20. The block 18 is equipped with detachable front and rear duplicate marking plates 21 which are held thereto by dove-tailed joints 22 and the portion of the block between these marking plates is formed to provide an upper transversely extending serrated cutting edge 23. The block 19 is equipped, in a similar manner, with front and rear plates 24 opposing the marking plates 21 and with an intermediate transversely extending serrated cutting edge 25 opposing the upper cutting edge 23. The plates 21 are both formed with characters representing the time clock number or other identifying symbol of the employee to whom the implement is assigned so that when the two members of the implement are pressed together with the record sheet interposed therebetween a duplicate marking of the time clock number or other identifying symbol is obtained, one of such markings being placed on one of the coupons and the other on the body of the sheet as hereinafter more particularly set forth.

75 The member 15 of the implement, as shown to advantage in Figures 2 and 3, is of substantially inverted U-shape in cross-section and the lower edges of the side portions 15a of the member are sharpened for a portion of their length and disposed at a slight angle 80

to provide longitudinal cutters 26 inclining downwardly and rearwardly from the ends of the transverse cutter 23 to a point 27 intermediate the length of said member. From 5 point 27 to the rear end of the member the depth of the side portions 15a is materially reduced and the lower edges of said side portions are provided with depending lugs 28. The members 12 and 15 are normally relatively positioned as shown to advantage in 10 Figure 5 wherein it will be noted that the marking plates and cutters of member 15 are elevated clear of a longitudinal slot 29 formed in and extending rearwardly from the forward edges of the side flanges 13 of the member 12, the lower edges of said slots being substantially in the plane of the block 19 and the plates 24. Members 12 and 15 are spread apart to assume this position by the spring 16 15 and the handle members 17 are normally prevented from being pressed together against the resistance of said spring by engagement of the lugs 28 with the upper end of a trigger 30. This trigger is mounted, near its upper 20 end, on a pivot 31 secured to the flanges 13 of the member 12 and is engaged at its lower end by a flat spring 32 which serves to normally hold the trigger in the position shown in 25 Figure 5.

30 In the use of the implement to record completion of an operation by the employee, one of the coupons 7 is inserted in the slot 29 until the free end of the coupon engages and swings the trigger 30 out of engagement with 35 the lugs 28 to permit the members 12 and 15 to be subsequently pressed together. When the free end of the coupon has been inserted in the slot to the extent necessary to release the trigger it will be understood that the free 40 end of the coupon is located between the rear printing plate 21 and the underlying plate 24 of the block 19, while the marginal portion of the body of the sheet immediately adjoining the attached end of the coupon is positioned 45 between the front printing plate 21 and the underlying plate 24. Preferably, in this position of the record sheet and the implement, the transverse and longitudinal cutters of the implement will coincide with the trans- 50 verse ruling or scored lines defining the coupon. When, after the insertion of the record sheet as aforesaid, the handle members 17 are pressed together the plates 21 will mark the body of the sheet and the coupon in duplicate as indicated at 33 in Figure 10 and at the 55 same time the coupon will be detached from the body of the sheet through the instrumentality of the transverse cutters 23 and 25 and the longitudinal cutters 26. When pressure 60 on the handle 17 is released spring 16 functions to return members 12 and 15 to the position shown in Figure 5 while spring 32 acts to reengage the trigger 30 with the lugs 28 to hold said members 12 and 15 against operation 65 until the record sheet and coupon is again

properly inserted between the marking portions of the members. The trigger, when returning to normal position, serves as a pusher to partially eject the coupon as will be readily understood. 70 It will also be observed that the indicia or markings on the body portion of the record sheet are located adjacent the ends of the coupon portions, so that the same may be used by the operator of the device as a guide in severing the coupons. By placing the nose or front end of the device adjacent a marking on the body portion and holding the device at right angles to the edge of the body portion, the operator may be assured that he will impart the additional markings in the desired positions and sever the coupon along the desired lines. Thus it may be said that the indicia or markings on the body portion serve as a guide in the operation independently of the lines defining the coupon. 80

In addition to the foregoing provision may be made for consecutively numbering the coupons marked by successive operations of the implement. A mechanism for accomplishing this is illustrated diagrammatically in Figures 1, 5 and 8. As shown in these figures a shaft 34 carrying the number wheels 35 is mounted in the side portions 15a of the member 15. One of the terminals of this shaft protrudes into an offset casing 36 formed by pressing outwardly a portion of one of the flanges 13 and is equipped with a ratchet 37, engaging a spring pressed pawl 38 mounted in the casing 36, and adapted to be rotated by cooperation with said pawl each time the members 12 and 15 are pressed together. As the specific details of construction by which the number wheels are operated in sequence forms no part of this invention 95 no description thereof is believed necessary. The member 12 carries a bed plate 38a for cooperation with the number wheels 35 and this bed plate is terminally recessed as indicated at 38b to afford the necessary clearance for the cutters 26 when the members 12 and 15 are pressed together. 100

In the modification shown in Figure 8 an ink ribbon 39, having its terminals attached to suitable winding and unwinding rollers 40 and 41 is trained around the number wheels 35 and the printing plates 21. In order to clear the transverse cutter 23 the ribbon is passed through suitable slots provided in the block 18 at opposite sides of the cutter and forming entrance and exit openings to a recess 42 in which is positioned a guide element 43 over which the ribbon is trained. Additional guide elements 43 may also be provided to support the ribbon in its passage from the number wheels 35 to the printing plates 21 and from the latter to the roller 40. 120

As a further modification, the longitudinal cutters of the member 15 may be serrated as indicated at 44 in Figure 9. 130

By providing either the transverse or longitudinal cutters, or both, with a serrated edge a distinctive outline is imparted to the detached margins of the coupon which is helpful in detecting fraudulent separation of coupons from the body of the sheet. If complete detachment of the marked coupon is not desired the cutters may be formed to merely perforate or otherwise weaken the marginal portions of the coupons.

Having thus disclosed what I now conceive to be a preferred apparatus for reducing the principles of the invention to practice it will be understood that various changes in the construction and design of such apparatus may be resorted to within the scope of the appended claims without departing from the spirit of the invention as defined thereby, and I may say specifically, but not exclusively, that when, in the claims, I refer to cutting or severing means or elements, I intend to cover not only means for actually severing a coupon but also means for providing for its severance as by scoring, creasing, perforating and the like.

What I claim is:

1. Apparatus of the character described comprising a marker including relatively movable members between which the material to be marked is gripped during the marking operation, a device normally arranged to hold said movable members in spaced relation and to thereby prevent operation of the marker, said device being in position to be engaged and displaced to an inoperative position by the material to be marked when the latter is properly placed between the said movable members of the marker, said device functioning when the movable members are separated subsequent to the marking operation, to push and partially eject the marked material from between said members.

2. Marking apparatus of the character described comprising a hand operated tool including relatively movable members between which the material is gripped during the marking operation, duplicate marking elements carried by said tool and arranged to simultaneously mark different portions of the said material, cutters carried by the tool and arranged around one of the marking elements to detach the portion of the material marked thereby and means functioning to eject the detached marked material from the implement subsequent to the marking operation.

3. Marking apparatus of the character recited in claim 2 in which the last named means normally serves to prevent operation of the marker and is arranged to be displaced to an inoperative position by engagement with the material to be marked only when the marker is in proper relation to said material.

4. Marking apparatus of the character de-

scribed comprising a hand operated tool including relatively movable members between which the material to be marked is gripped during the marking operation, duplicate marking elements carried by said tool and arranged to simultaneously mark different portions of said material, a numbering device of the progressive type also carried by the tool and operating in unison with the marking means to consecutively number portions of the material marked by successive operations of the tool, cutters carried by the tool and arranged around one of the marking elements to detach the portion of the material marked thereby and means functioning to eject the marked material from the implement subsequent to the marking operation.

5. A device of the character described comprising, pivoted members having their operative portions substantially U-shaped in cross section, cooperative marking elements carried by and located within said members, cooperative cutting elements carried by and located within said members, and additional cooperative cutting elements constituted by the edges of said U-shaped portions.

6. A device of the character described comprising, pivoted members having their operative portions substantially U-shaped in cross section, cooperative marking elements carried by and located within said members, cooperative cutting elements carried by and located within said members, additional cooperative cutting elements constituted by the edges of said members, and cooperative numbering elements carried by and located within said U-shaped portions.

7. A device of the character described comprising, pivoted members, cooperative marking elements carried partly by one and partly by the other of said members, and cooperative cutting elements carried partly by one and partly by the other of said members, said marking and cutting elements being adapted to operate upon a sheet inserted between the pivoted members and the cutting elements being designed to perform an incision on the sheet in a non-straight line.

8. A device of the character described comprising, relatively movable members, cooperative marking elements carried by said members and spaced from each other, cooperative cutting elements transversely disposed in said members between said marking elements, and additional cooperative cutting elements constituted by said members themselves.

9. A device of the character described comprising, relatively movable members, cooperative marking elements carried by said members and spaced from each other, cooperative cutting elements transversely disposed in said members between said marking elements, an auxiliary marking device also carried by said members, and additional coop-

erative cutting elements located between said first named marking elements and the auxiliary marking device.

10. A device of the character described comprising, relatively movable members, cooperative marking elements carried by said members and spaced from each other, cooperative cutting elements transversely disposed in said members between said marking elements, an auxiliary marking device also carried by said members, and additional cooperative cutting elements located between said first named marking elements and the auxiliary marking device and being constituted by said members themselves.

In testimony whereof I hereunto affix my signature.
